PORTABLE CLOTHESLINE PROP

Wilbert Knight and Claris E. Pritchard,
Pittsburgh, Pa.

Application October 2, 1947, Serial No. 777,532

1 Claim. (Cl. 248—353)

1

This invention relates to a portable and adjustable clothes line prop or pole that is convenient, handy and economical to manufacture.

An object of the invention is to provide a prop or pole of this character, that is easily adaptable for inside or outside use, and is easily adjusted to any height desired within the length of the pole as originally designed.

Another object of the invention is to provide a prop or pole of this character, having a quick, detachable clothes line means at the upper end thereof.

With the above and other objects and advantages in view, the invention consists of the novel details of construction, arrangement and combination of parts more fully hereinafter described, claimed and illustrated in the accompanying drawing in which:

Figure 1 is an elevational view of an embodiment of the invention in full extended position;

Figure 2 is an enlarged, vertical, sectional view, partly broken away, on the line 2—2 of Figure 1 and

Figure 3 is a sectional view on the line 3—3 of Figure 1.

Referring more in detail to the drawing, the clothes line prop or pole embodying the invention is generally designated by the reference numeral 10. The prop or pole 10 comprises an outer tubular member 11 and an inner tubular member 12, the member 12 being telescopically received in the member 11 with enough clearance to permit free sliding movement of the member 12, but to prevent any lateral movement thereof. The tubes can be made from rust resistant metals or suitable composition having the required strength for the purpose designed or they may be made from a suitable plastic. Thus the prop or pole, due to the material from which it is made, will withstand any weather conditions encountered during its use.

The lower end of the member 11 is provided with a removable tip 13, which may be made of rubber, rubber composition or plastic or any other material suitable for this purpose. That is to prevent the prop or pole from slipping on cement or concrete surfaces or any other type of surfaces which may be encountered during the use of the prop or pole.

Extending downwardly from the upper end of the member 11 is an elongated slot 14 having short downwardly inclined branch slots or inserts 15 formed in communication therewith in the member 11.

The member 12 has a rod or lever 16 which

2

extends through the diameter of the member at right angles thereto, to be secured at its end 17 to the member 12, as shown in Figure 2. The rod or lever 16 extends outwardly of the member 12 through an opening 18 therein, and is provided with a knob 19 on its outer end. When the member 12 is inserted into the member 11, the rod or lever 16 is received in the slot 14 in the member 11.

10 If the rod or lever 16 remains in the slot, the members 11 and 12 can be easily moved with relation to each other. In use, however, when the rod or lever 16 is inserted into one of the branch slots 15, as shown in Figure 1, the members 11 and 12 will be retained in adjusted fixed relation to each other. With the rod or lever 16 extending entirely through the diameter of the member 12, binding of the two members is eliminated during the sliding movement of the members.

20 The upper free end of the member 12 is provided with diametrically opposed openings 20 to receive the outturned ends 21 of the quick detachable helical shaped spring clamp 22. The clamp 22 is adapted to receive a clothes line between the helicals thereof and, being flexible, by the nature of the material, will permit a slight sway of the prop or pole during a stiff breeze to prevent falling of the prop or pole.

25 In use, the prop or pole, as described, is used in the conventional manner, except that it is adjustable for height to raise a clothes line connected to the clamp at any desired height from the surface on which the lower end of the prop or pole is resting.

30 It is believed that the operation and construction of the invention will be apparent to those skilled in the art, and it is to be understood that changes in the minor details of construction, arrangement and combination of parts may be resorted to, provided they fall within the spirit of the invention and the scope of the appended claim.

35 Having thus described the invention, what is claimed as new and desired to be secured by Letters Patent is:

40 A quick detachable helically shaped spring clamp for a tubular telescopically arranged clothes line prop having diametrically opposed openings in the upper end thereof, comprising a pair of straight opposed and aligned leg portions, outturned ends on the lower end of each of said leg portion at right angles thereto, said outturned ends adapted to be inserted into the openings in 45 said prop to retain said clamp on said prop when

said leg portions are compressed inwardly and said clamp comprising two helicals providing a V-shaped clamp which is adapted to be engaged with a clothes line and retained on the clothes line by the spring action of said spring clamp when said leg portions are released.

WILBERT KNIGHT.
CLARIS E. PRITCHARD.
